[57] ABSTRACT

A vibrator mechanism is provided which may be used for many purposes such as screening aggregates, driving piles, casings, actuating trenching plows, etc. More particularly the mechanism contemplates changing the directions of the vibratory oscillations from a straight line reciprocation to a "figure eight" motion, and also changing the plane in which these motions occur.

3 Claims, 3 Drawing Figures

FIG.1

FIG.2

FIG.3

MULTIPLE-WAY VIBRATOR

SUMMARY OF THE INVENTION

A typical construction of the mechanism involves parallel shafts geared to each other and mounting individual eccentric weights, the weight or weights on at least one shaft being shiftable axially relative to the weight or weights on the other shaft, and the shafts being adjustable angularly with respect to each other by disengaging and reengaging their gears.

BRIEF DESCRIPTION OF THE DRAWINGS

FIG. 1 is a plan view of a framing or base plate mounting the vibratory elements.

FIG. 2 is a fragmentary top view corresponding to a portion of FIG. 1 but with the parts shifted to provide a different vibratory movement.

FIG. 3 is a section on line 3—3 of FIG. 1.

DETAILED DESCRIPTION

The base 1 mounts pairs of bearings 2, 2 and 4, 4 for parallel shafts 6, 7 respectively carrying interengaged equal gears 9, 10 keyed to the left-hand ends of the shafts. A pulley 11 on the other end of shaft 6 is driven by a motor (not shown). An eccentric weight comprising weight members 13 spaced apart longitudinally of shaft 6 is keyed to shaft 6, and an eccentric weight 14 is keyed to shaft 7.

Rotation of pulley 11 rotates the shafts and weights to set up reciprocal thrusts in base 1 which are transmitted as vibrations to the plow or other equipment upon which it is mounted. Gear 9 is pressed by spring 18 against a collar 17 on the left-hand end of shaft 6 where it meshes with gear 10 and rotates the latter and the weights mounted thereon.

By compressing spring 18, gear 9 may be shifted to disengage gear 10 and may be rotated angularly any desired amount to vary the angular relation of weight 13, 14 to each other and when the gear is released spring 18 thrusts gear 9 into mesh with gear 10 in the new angular relation.

Weight 14 is shiftable lengthwise of shaft 7 and may

be positioned as desired so as to be in centered relation to weights 13 or to be positioned closer to one of bearings 4.

A shaft 19 is rotatably mounted in bearings 2 on the base plate and threaded through yoke 15, the terminals 16 of which embrace weight 14 and are apertured to slidably receive shaft 7, thus providing for ready adjustment of weights 14 longitudinally of shaft 7 and relative to weights 13. To facilitate rotation of shaft 19 it is provided at its ends with knurled knobs 20.

With the weights disposed as shown it is a simple matter to vary the vibratory thrust of the mechanism or to vary the vibration from a straight line reciprocation or to introduce stipulated increments of figure eight movements in the plane of the base plate.

I claim:

1. A vibrating mechanism comprising a base member, two shafts side by side with individual spaced journals on said base member, interengaged gears on said shafts, eccentric weights carried on said shafts, the gear on one shaft being movable axially of that shaft to disengage the gears to provide for relative rotation of the shafts whereby the weight on one shaft is shiftable angularly about the axis thereof irrespective of the weight on the other shaft, and yielding means for reengaging the shafts after their simultaneous rotation.

2. A vibrating mechanism as described in claim 1 in which the weight on one shaft comprises separate weight members spaced apart lengthwise of the shaft and the weight on the other shaft is positioned between said separate weight members and is shiftable in opposite directions longitudinally of the shaft relative to the spaced weight members on the first shaft.

3. A vibrating mechanism as described in claim 2 including a threaded shaft rotatably journaled on said base member parallel to said other shaft, a yoke threadably mounted on said threaded shaft and having terminals embracing said weight on said other shaft for shifting said weight longitudinally of said other shaft responsive to rotation of said threaded shaft.
